Patented June 23, 1914.

2 SHEETS—SHEET 2.

UNITED STATES PATENT OFFICE.

JAMES F. BAILEY, OF JACKSONVILLE, FLORIDA, ASSIGNOR OF ONE-HALF TO FRANKLIN T. SUTHERLAND, OF JACKSONVILLE, FLORIDA.

RECORDING-CLOCK.

1,101,385.

Specification of Letters Patent. Patented June 23, 1914.

Application filed May 6, 1913. Serial No. 765,947.

To all whom it may concern:

Be it known that I, JAMES F. BAILEY, a citizen of the United States, residing at Jacksonville, in the county of Duval and State of Florida, have invented certain new and useful Improvements in Recording-Clocks; and I do hereby declare the following to be a full, clear, and exact description of the invention, such as will enable others skilled in the art to which it appertains to make and use the same.

This invention comprehends improvements in recording clocks and relates more particularly to those which are especially adapted for use in recording the time of arrival and departure of workmen, watchmen, and other employees; for use in factories to determine the length of time consumed upon a certain piece of work; and for all other purposes of a similar nature.

The primary object of the invention lies in the provision of a recording clock which may be simply constructed, easily operated, and which will accurately record time intervals.

Another and more specific object of the invention is to provide a recording clock having an hour dial and a minute dial which carry raised numbers on their peripheries corresponding to the numbers on the face thereof, strips of carbon and recording paper movable over these raised numbers, a platen block, and a punch key for forcing the platen block toward the raised numbers, whereby an impression will be made upon the recording paper.

With these and other objects in view, as will become more apparent as the description proceeds, the invention consists in certain novel features of construction, combination, and arrangement of parts, as will be hereinafter described and claimed.

For a complete understanding of my invention, reference is to be had to the following description and accompanying drawings, in which,

Figure 1 is a front elevation of my recording clock, Fig. 2 is a section on the plane of line 2—2 of Fig. 1, Fig. 3 is a vertical section taken on the plane of line 3—3 of Fig. 2, Fig. 4 is a vertical transverse section through the clock, and, Fig. 5 is a fragmentary sectional view, partly in eleva-

tion, illustrating a slightly modified form of clock constructed in accordance with my invention.

In the preferred embodiment of my invention, I provide a case, generally designated 10, having a front wall 11, and a rear wall 12, side walls 13 and 14, and top and bottom walls. A partition 15 extends vertically with the case and divides the same into compartments 16 and 17, the former containing the clock and the latter the time dials and recording mechanism.

The clock mechanism which is of the usual type, is contained within the housing 18, and includes the arbor 19 and sleeve 20. An hour dial 21 is rigid with the forward end of the sleeve 20 and has raised figures 22 formed upon its periphery which correspond to the figures upon the face of the dial. A minute dial 23 is rigidly secured to the forward end of the arbor 19 and carries a rim 24 which is secured in spaced relationship to the periphery of the dial properly by means of the spokes 25. The rim is formed upon its periphery with a flange 26, the purpose of which will be hereinafter explained, and carries in addition to the flange, raised numbers 27 which correspond to the numbers upon the face of the minute dial. The dials may be viewed through a circular opening 29 formed in the front wall of the case and covered by a glass plate 30 on which is marked an indicator or pointer 31. It will be noted that the construction of the minute dial is such as to expose to view the numbers of the hour dial which are carried upon a strip 32.

The time is recorded upon a paper ribbon 33 which is automatically unwound from the roll 34 that revolves with a shaft 35 which is journaled through the front wall 11 and partition 15 of the case. The paper ribbon is passed between the two pair of guide rods 36 and the feed rollers 37 which are preferably faced with rubber. These rollers are keyed to the shafts 38 which are also journaled through the front wall and partition 15 of the case. The side wall 14 of the case is slotted, as indicated at 39, to permit the paper to run therethrough. An impression ribbon 40 is wound upon the rolls 41 carried by the shafts 42 and runs between the pairs of guide rods 36 in con-

tact with the recording ribbon 33. Referring to Figs. 3 and 4, it will be seen that the recording ribbon 33 passes over the dial 21 and rim 24 in juxtaposition to their highest points and that the impression is immediately above the recording rim.

In order that the raised numbers may be caused to leave an impression upon the recording ribbon, I provide a platen block 43 having a head piece 44, which is slidable along the guide rods 45 secured to the top wall of the case. The guide rods are enlarged at their lower ends for engagement with the expansive spiral springs 46 which hold the platen block normally in its raised position. When the block is forced downwardly, it forces the platen block and the recording ribbon against the figures 22 and 27, and causes them to leave their impression upon the recording strip.

In order that each operation of the impression block may be caused to feed the recording ribbon so as to bring a fresh portion over the uppermost points of the time dials, I provide a connecting rod 47, which is secured at one end to one of the guide rods between the spiral spring and the head 44 and at its other end to a pin 48. The pin extends through a longitudinal slot formed in the connecting rod. A depending pawl 47 is pivoted to the connecting rod and held in engagement at its lower end with a toothed rim 50 carried by the low feed roller by means of the contractile spring 51. A downward movement of the platen block causes a similar movement of the pawl and when the platen block is returned to its normal position the pawl rotates the lower feed roller slightly and causes the longitudinal movement of the recording ribbon 33.

When the clock is used for the purpose of recording the time of employees, a plurality of punch keys are provided, one for each employee. Each of these keys 45 comprises a shank 52 which is of a reduced diameter for a portion of its length adjacent its lower end, as indicated at 53, and which carries a head 54 upon the other end thereof. The reduced portion of the shank 50 may be inserted through a longitudinal opening formed in the platen block and head piece, and extends flush with the lower end thereof. A number is raised upon the extremity of the reduced portion 53 of the shank and is disposed beyond the lower extremity of the platen block. Different numbers are placed upon the various punch keys and indicate to which employee each key belongs.

When a punch key is inserted through the platen block and forced inwardly, the block is carried with it and forces the two ribbons toward the raised numbers 22 and 27 and causes an impression to be left upon the recording ribbon. The number upon the

end of the punch key forces the two ribbons toward the flange 26 and leaves its record upon the recording strip. In Fig. 2 the result of the operation of the platen block by the use of a number 4 punch key 70 at twelve-thirty, is shown.

From the foregoing description taken in connection with the accompanying drawings, it will be seen that I have provided an extremely simple recording clock which may be operated so as to record the time at different intervals upon a recording strip.

It will be understood that the raised numerals upon the periphery of the hour dial and upon the rim 24 are located very close together so that a proper impression is made regardless of the time at which the platen block is forced downwardly. The shafts which carry the various rolls are provided with knobs 26 so that they may be manually rotated.

In the form of my invention shown in Fig. 5, 55 designates a casing containing clock-works of any type and 56 and 57 indicate the minute and hour hands, respectively, of a clock, which may be viewed through the glass plate 58. The shaft 59 of the minute hand is extended rearwardly beyond the clock-works and carries a disk 60, which is provided with raised characters upon its periphery. The disk 61 is equal in diameter to the disk 60 and is rotated by the sleeve 62 of the hour hand. This disk is also provided with raised characters upon its periphery. 63 designates the paper recording strip and 64 the platen ribbon. When the impression block 65 is forced downwardly by the key 66, the time is stamped upon the recording strip and the number of the key is also stamped thereon. The block 67 is supported upon the casing 55 directly under the key 66 upon a level with the highest character upon the disks. The means for supporting the platen block 65 and the means for actuating the ribbons 63 and 64 are the same as those heretofore described and therefore need not be explained further.

It is to be understood that while I have shown and described the preferred embodiments of my invention, I do not wish to be limited to these exact constructions, combinations, and arrangements of parts, but may make such changes as will fall within the spirit and scope of the invention.

Having thus described my invention, what I claim is:—

1. The combination with a clock having an hour dial and a minute dial formed with raised figures on their peripheries, of time recording mechanism including a recording strip and an impression strip, a spring pressed platen block to force the impression strip and recording strip toward the peripheries of the dials, and a punch key for actu-

ating the platen block, said punch key extending entirely through the block and having a character raised upon its extremity.

2. The combination with a case, of a clock 5 positioned therein having an hour dial and a minute dial, said dials being formed with raised figures upon their peripheries, a recording ribbon movable over the peripheries of the dials, an impression ribbon, guide rods 10 depending from the case, a platen block movable along said guide rods toward the dials, springs for holding the platen block normally in its raised position, said block being formed with a longitudinal opening 15 extending therethrough, and a punch key insertible within said opening, the inner extremity of the key projecting beyond the inner end of the platen block and having a character raised thereon, a downward movement 20 of the punch key causing the impression block to force the ribbons toward the peripheries of the dials.

3. In a clock of the character described, a pair of rotatable dials having characters 25 raised on the peripheries thereof, one of the dials being also formed with a flange extending around its periphery, a recording ribbon movable longitudinally above the dials in close proximity to the peripheries 30 thereof, an impression ribbon positioned to the outside of the recording ribbon, a platen block having an opening extending therethrough, and a punch key insertible within said opening and having a character raised 35 on the extremity thereof, a downward movement of the punch key causing a similar movement of the platen block, the punch key forcing the recording ribbon against said flange and the platen block forcing the 40 recording ribbon against the characters upon the peripheries of the dials.

4. The combination with a case, of a clock 45 positioned therein, said clock having an hour dial and a minute dial revoluble in vertical planes, the dials being formed with raised characters upon their peripheries, a record-

ing ribbon, an impression ribbon, feed rollers through which said recording ribbon passes, a ratchet formed upon one of the feed rollers, a reciprocal platen block, a connecting rod secured at one end to the block and at the other end to said case, and a spring 50 pressed pawl depending from the connecting rod and engaging the ratchet, an upward movement of the platen block causing the 55 pawl to rotate one of the feed rollers.

5. In a recording clock, the combination with a pair of dials of equal diameters having characters formed upon their peripheries, means for receiving an impression of said 60 characters, the dials being positioned one behind the other in close relation and provided upon their forward faces with visual characters, the outermost dial being annularly recessed to expose the visual characters upon 65 the rear dial.

6. In a recording clock the combination with a pair of dials having characters formed upon their peripheries, of means for receiving an impression of said characters, 70 the dials being positioned one behind the other and formed upon their forward faces with visual characters, the outermost front dial being formed so as to expose the visual characters upon the rear dial. 75

7. In a recording clock the combination with a stationary pointer, a pair of revolvable dials positioned to the rear of said pointer, the dials being formed upon their peripheries with recording characters, means 80 for receiving an impression of said recording characters, and visual characters formed upon the forward faces of the dials, the forward dial being formed so as to expose the 85 visual characters upon the rear dial.

In testimony whereof I affix my signature in presence of two witnesses.

JAMES F. BAILEY.
